UNITED STATES PATENT OFFICE

REINHOLD A. NORLING, OF AURORA, ILLINOIS, ASSIGNOR TO INDEPENDENT PNEUMATIC TOOL COMPANY, OF CHICAGO, ILLINOIS, A CORPORATION OF DELAWARE

BALANCED THROTTLE VALVE FOR PNEUMATIC TOOLS

Application filed February 14, 1927. Serial No. 167,884.

This invention relates to improvements in throttle valve mechanism for pneumatic tools, such as chipping hammers, riveting hammers, etc.

5 Much trouble has been experienced in the past with the throttle valve parts rapidly wearing out and thus producing inefficient tools. In a straight throttle valve as heretofore made, the stem and valve member have been made in two parts with the stem fitting loosely in a recess in the adjacent end of the valve member. Live air would get in between the valve member and the stem and exert a pressure to force the stem against the trigger lever with the result that the trigger would rub against the stem in the actuation of the parts, and thus, not only wear out the end of the stem and the part of the trigger 10 engaging the same, but also enlarge the hole in the trigger through which the pivot pin extends to so produce a leaky assembly. A puppet type of throttle valve with the beveled seat could be lapped in when it started to leak, 15 but this type of valve as heretofore made would be out of balance when the valve is open, and, as the pressure against the trigger would be equal to the area of the stem multiplied by the air pressure, the pressure 20 against the trigger would cause the same to rub against the end of the valve stem and effect rapid wearing of the parts.

The main object of my invention is to provide a throttle valve of the puppet type and 25 have the valve balanced when open, and thus prevent pressure against the trigger and consequent wear on the parts, thereby overcoming the objections as above noted.

The invention consists further in the construction of my improved valve assembly, 30 and, as shown in the drawings—

Fig. 1 is a side elevational view of a chipping hammer equipped with a throttle valve mechanism of my invention;

45 Fig. 2 is an enlarged vertical sectional view through said mechanism and the associated portions of the handle of the tool;

Fig. 3 is a horizontal sectional view taken on line 3—3 of Fig. 2; and

50 Fig. 4 is a vertical sectional view showing

another form of my improved valve mechanism.

The tool shown in Fig. 1, has a barrel 1 and a handle 2, these parts being connected together at their adjacent ends as usual in tools of this kind. The portion 3 of the handle is grasped by the hand of the operator when holding the tool, and contains the throttle valve mechanism of my invention. This mechanism controls the supply of compressed or live air to the barrel of the tool for reciprocating the hammer piston therein for delivering the required blows to the chisel or other working implement 4 inserted in the outer end of the barrel, as in tools of this 55 general character.

As shown in Fig. 2, the handle portion 3 is provided with a bore 5 extending vertically therethrough to receive the valve bushing 6, which has a tight fit in said bore. Said bushing 6 has a tapered valve seat 7 therein about midway between its ends, with the seat facing the lower end of the bushing. A puppet valve member 8 is located in the bushing 6 below said seat, and co-operates therewith to control the passage of live air through the bushing through port holes 9, 10 in the bushing on opposite sides of said seat. The valve member 8 has vertically disposed and 60 axially aligned guide stems 11, 12 on opposite sides thereof. Sleeves 13, 14 are located in the bushing 6 on opposite sides of the valve seat 7, and the stems 11, 12 are slidably mounted in these sleeves so as to guide the valve 65 in its movements on and off its seat. The bore of the bushing 6 is so made as to hold the sleeves 13, 14 in axial alignment and thus maintain the valve member 8 central in the bushing in its movements on and off its 70 seat. The valve member 8 does not have a tight fit in the bushing 6, sufficient clearance 75 being provided so that the live air entering the bushing through the port holes 9 on the under side of the valve seat 7 may freely flow around the sides of the valve member 8 to reach the outlet port holes 10 when the valve member is off its seat, as shown in Fig. 80 85

2. Thus when the valve member 8 is in its open position, that is, off its seat 7, the air pressure on opposite sides of the valve, that 90 95 100

is, above and below the same, will be the same, and the valve member 8 will be balanced at its seat. The guide stems 11, 12 have a close fit in their respective sleeves 13, 14, so as to prevent live air within the bushing 6 from escaping through said sleeves.

The upper sleeve 13 terminates at the upper end of the bushing 6, as shown in Fig. 2, and, as there illustrated, the upper stem 11 extends above the upper ends of both the bushing 6 and the sleeve 13 so as to be in position to be engaged by a downwardly facing lug 15 on the inner side of the valve opening trigger lever 16, which is pivoted by a pin 17 to the handle portion 3 in a slot 18 therein on the rear side of the bore 5. The lever 16 extends above the handle portion 3 so that the upper end of said lever may be depressed by the thumb of the hand of the operator grasping the handle for pushing the lug 15 down against the stem 11 for moving the valve member 8 off its seat 7. A coiled spring 19 surrounds the lower stem 12 below the valve member 8 and presses upward against the same to move the valve member 8 onto its seat to close the valve when the operator releases his pressure on the upper end of the lever 16. In the upward movement of the valve member 8 by the spring 19, the upper stem 11 is pushed upward against the lug 15 so as to swing the trigger lever back to its starting position. The lower end of the spring 19 bears against an abutment inside of the lower sleeve 14 and holds it against the inner end of a cap 20, which is screwed into the lower end of the bushing 6 to close the same, as shown in Fig. 2. The lower end of the sleeve 14 is reduced to enter the cap 20. This provides the sleeve 14 with a downwardly facing shoulder 21, which is held by the spring 19 against the inner end of the cap. This, together with the stem 12 closing the portion of the sleeve in which it has sliding movement, acts as a seal to close the lower end of the bushing 6 to the escape of air therefrom. With the sleeve 14 separate from the cap 20, the bushing 6 and not the cap maintains the sleeve 14 in axial alignment with the upper sleeve 13 for keeping the valve member 8 central. Thus the reduced lower end of the sleeve 14 may have a loose fit in the cap 20 and sufficient clearance or side play allowed between the two so that, if the threads of the cap are not made true or concentric with the sleeve 14, the latter will not be thrown out of alignment to effect the central position as required for the valve member 8.

The cap 20 has a vent hole 22, which exposes the lower end of the lower stem 12 to the atmosphere. The top end of the upper stem 11 is also exposed to the atmosphere through the upper open end of the bore 5, as shown in Fig. 2. With the ends of the

stems substantially equal in area there are equal pressure conditions on the ends of the stems, and this together with equal pressures on opposite sides of the valve member 8 when off its seat, produces a balanced valve when open. Thus the trigger lug 15 and its pivot pin 17 are both relieved of pressure when the valve is open, with the result that the wear on these parts, as well as on the upper end of the stem 11 where it engages the lug 15, is reduced to the minimum. With a puppet type of valve, as disclosed herein, the valve seat 7 takes the pressure of the spring 19 and of the air on the underside of the valve member 8 when the latter is closed, with the result that the trigger lever 16 and its parts are not under pressure at that time. The construction therefore is dependable and has a long life. Moreover, with a puppet valve it is possible to keep the valve tight when closed, due to the fact that the valve member 8 may be lapped against its seat 7 to insure a tight fit at all times. This is a decided advantage in conjunction with a balanced construction.

The handle portion 3 has an air intake passage 23, to which the supply hose is connected. This passage opens directly into a recess 24 provided about the outer side of the bushing 6 at the port holes 9 beneath the valve seat 7. These ports are so disposed that the valve member 8 on being opened uncovers the ports in succession and thus allows for a gradual admission of air. This is accomplished by having all the ports of an equal length but positioned so that one port extends beyond another, as shown in Fig. 2. The portion of the bushing above the ports 10 is reduced so that the bore 5 provides an air receiving chamber into which the air flows from said ports before entering the handle passage 25, which leads to the distributing valve (not shown) and by which the flow of live air to the opposite ends of the barrel is controlled, as in pneumatic tool design.

The cap and sleeve, however, could be made in one piece with special attention to workmanship. In Fig. 4, I have shown these parts in one piece or integrally connected. There the lower sleeve is indicated by 14^a and the cap 20^a. In this construction it is essential that the screw threads provided on the cap and in the bushing 6 be concentric with respect to each other and to the axis of both sleeves, so that the valve stems will be held central so as not to be thrown out of alignment to bind, as would be the result should the threads not be accurately formed. The rest of the structure illustrated in Fig. 4 is the same as that heretofore described, and the same reference characters are employed to indicate similar parts.

With my improved throttle valve mechanism, the valve is non-leakable when not in use.

use, that is, closed; and balanced when in use, that is, open. It prevents pressure against the trigger lever and consequent wear on the parts. The long sleeve for the upper stem 5 11 is also an improvement and if worn can be replaced without replacing the more expensive main bushing 6. In both forms of structure shown, the lower sleeve can also be readily and easily removed. With the form 10 15 shown in Fig. 2, the threads in the bushing 6 and on the cap need not be accurately machined, and thus the expense of these parts is kept to the minimum.

The details of structure and arrangement 15 20 of parts shown and described may be variously changed and modified without departing from the spirit and scope of my invention.

I claim as my invention:

1. A throttle valve mechanism for pneumatic tools, comprising in combination with the handle of the tool having an air supply 25 30 passage and a bore therein with the bore extending across said passage, of a bushing fitting in said bore and dividing the same into upper and lower chambers in said passage, said bushing having a valve seat therein and air ports extending through said bushing on opposite sides of said seat and opening into the respective chambers, a puppet valve member in said bushing for said seat and having guide stems on opposite sides thereof and supported through the medium of said bushing, said stems having their outer ends of substantially equal area and exposed to the atmosphere 35 40 to provide a balanced valve when off said seat, and means for moving the valve member on and off its seat.

2. A throttle valve mechanism for pneumatic tools, comprising in combination with the handle of the tool having an air supply 45 50 passage and a bore therein with the bore extending across said passage, of a bushing fitting within said bore and dividing the same into upper and lower chambers in said passage, said bushing having a valve seat therein and air ports extending through the bushing on opposite sides of said seat and opening into the respective chambers, a puppet valve member in said bushing for said seat and having guide stems on opposite sides thereof and supported through the medium of said bushing, said stems having their outer ends of substantially equal area and exposed to the atmosphere 55 60 to provide a balanced valve when off said seat, said valve having its portion on the inlet side of said seat fitting within said bushing so as to uncover the ports on such side of the seat in succession as the valve member is moved off of its seat, and means for moving the valve member on and off its seat.

3. A throttle valve mechanism for pneumatic tools, comprising in combination with the handle of the tool having an air supply 65 70 passage and a bore therein with the bore extending across said passage, of a bushing fit-

ting within said bore and dividing the same into upper and lower chambers in said passage, said bushing having a valve seat therein between its ends and air ports extending through the bushing on opposite sides of said seat and opening into the respective chambers, sleeves 70 75 removably fitted in the bushing on opposite sides of said seat and held in axial alignment by said bushing, a puppet valve member in the bushing for said seat and having guide stems slidably mounted in and supported by said sleeves, said stems having their outer ends of substantially equal area and exposed to the atmosphere, and means for moving the valve member on and off its seat. 80

4. A throttle valve mechanism for pneumatic tools, comprising a vertically disposed bushing having a valve seat therein between its ends, upper and lower sleeves removably fitted in the bushing on opposite sides of said seat and held in axial alignment by said bushing, a puppet valve member in the bushing for said seat and having guide stems slidably mounted in said sleeves, a cap made separate 85 90 from the lower sleeve and screwed into the lower end of the bushing to close the same, said cap having a vent hole to expose to the atmosphere the end of the stem in the lower sleeve, said lower sleeve having a reduced lower end with a loose fit in said cap and providing a shoulder to seat thereon, a spring for holding the lower sleeve seated on said cap and for closing the valve member on its seat, and a pivoted trigger lever engaging the upper stem for moving the valve off its seat. 95 100

5. The combination with a handle for a pneumatic tool having an air supply passage therein with a vertically disposed bore extending across the same, of a bushing fitted in said bore and having a tapered valve seat therein with air ports on opposite sides of said seat and communicating with the portions of the passage as divided by the bushing, upper and lower sleeves fitted in said bushing on opposite sides of said seat, a puppet valve member for said seat and having guide stems on opposite sides thereof and slidably supported in said sleeves, a cap closing the lower end of the bushing and having a vent hole therein to expose to the atmosphere the end of the stem in the lower sleeve, the upper end of the stem in the upper sleeve being exposed to the atmosphere through the upper end of said bore, and a trigger lever pivoted to the handle at one side of the bore and having a lug engaging the top end of the upper stem for moving the valve off its seat, and a spring surrounding the lower stem for holding the lower sleeve against the cap and for moving the valve member to its seat. 115 120 125

In testimony whereof I affix my signature this 8th day of February, 1927.

REINHOLD A. NORLING.
